UNITED STATES PATENT OFFICE

170,347

COMBINATION RADIO-TELEVISION
CABINET CONTROL PANELSamuel E. Adler, Chicago, Ill., assignor to Admiral
Corporation, Chicago, Ill., a corporation of
Delaware

Application February 12, 1953, Serial No. 23,579

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combination Radio-Television Cabinet Control Panel, of which the following is a specification, reference being had to the accompanying drawings, forming part thereof.

Fig. 1 is a front elevational view of a combination radio-television cabinet control panel, embodying my new design;

Fig. 2 is a similar view thereof with the center plate in lowered position;

Fig. 3 is a top plan view thereof as it is arranged in Fig. 1;

Fig. 4 is an elevational view of the left hand end thereof with the center plate in lowered position;

Fig. 5 is a sectional view indicated by line 5—5 of Fig. 3; and

Fig. 6 is a sectional view indicated by line 6—6 of Fig. 3.

The dominant features of my design reside in that portion shown by full lines in the drawings.

I claim:

The ornamental design for a combination radio-television cabinet control panel, as shown and described.

SAMUEL E. ADLER.
